UNITED STATES PATENT OFFICE.

JOHN E. ELWING, OF SUMMIT, WASHINGTON.

SHINGLE-BAND-NAILING MACHINE.

No. 910,050.

Specification of Letters Patent.

Patented Jan. 19, 1908

Application filed June 12, 1908. Serial No. 438,139.

To all whom it may concern:

Be it known that I, JOHN E. ELWING, a citizen of the United States of America, residing at Summit, in the county of Chehalis 5 and State of Washington, have invented certain new and useful Improvements in Shingle - Band - Nailing Machines, of which the following is a specification, reference being had therein to the accompanying drawing.

This invention relates to nailing machines and especially to those for nailing a strip of iron to a strip of wood to form a shingle band such as is used in bundling shingles, and has for its object to provide a device 10 into which the nails may be dumped and which will feed them automatically into nailing position at the proper time.

Further objects are to provide a gage by which the iron and wooden strips are placed 15 in proper nailing positions, and to so improve the construction of such machines as to produce a machine which will be cheap to make, easy to operate and easy to keep in repair.

I attain these objects by the devices and mechanisms illustrated in the accompanying drawings, in which—

Figure 1 is a side elevation of my completed machine mounted and ready to use; 30 Fig. 2 is a front elevation thereof showing it in the act of nailing; Fig. 3 is a vertical longitudinal section of the nail hopper showing the feeding mechanism and the nail conveyer leading therefrom to the nailer; 35 Fig. 4 is a vertical transverse section on the line 4—4 in Fig. 3; Fig. 5 is a vertical cross section on the line 5—5 in Fig. 3; Fig. 6 is a vertical cross section of one of the nail conveyers or slides; Fig. 7 is a horizontal cross 40 section of the nailer on the line 7—7 in Fig. 10, showing the parts in the positions which they occupy at the end of a nailing stroke, and Fig. 8 is a similar view showing the parts in the positions they occupy at the beginning of a nailing stroke; Fig. 9 is a full 45 sized view of the shifting spring; Figs. 10 and 11 are vertical longitudinal sections of the nailing mechanism in the beginning and ending of its nailing stroke respectively; and 50 Figs. 12, 13 and 14 are vertical cross sectional views of the nailing mechanism showing the parts in the positions of starting the nailing stroke, just subsequent to starting the nailing stroke and finishing the nailing 55 stroke respectively.

Similar numerals of reference refer to similar parts throughout the several views.

This invention consists of an open ended hopper into which a suitable number of nails may be placed; means in the hopper for feeding the nails forward at a uniform rate; a sliding inclined conveyer; means for agitating the conveyer; a nail valve at the end of the conveyer to admit one nail at a time to the nailing apparatus at the proper 60 moment; a vertical sliding nail guide adapted to prevent the nail delivered thereto from falling into the position for nailing until the nail driver starts on its downward stroke, and to guide the nail into nailing position at 65 the proper time; and a vertical acting nail driver adapted to engage the nail in the guide and to drive it through the iron strip and into the wooden strip.

This invention also consists in providing 70 a spillway by means of which defective nails are turned to one side and are not fed into the nailing mechanism; and in certain gages for guiding the strips to be nailed so that they will occupy their proper relative 75 positions.

Referring now to the drawings, the nail hopper is shown in Figs. 1 to 5, and consists of a metal body having inclined sides 1 but without any front, and having its bottom 2 80 inclined slightly forwards. The bottom 2 is channel-shaped and holds a sliding feeder 3 formed with a number of steps or teeth 4 on its upper size. This feeder 3 can slide 85 longitudinally in the channel 2 of the hopper and is actuated by means of a lever 5 pivoted to the standards at 6 and operated by means of a connecting bar 7 secured to the agitator hereinafter described, the connection between the connecting bar and the 90 agitator being adjustable in a slot 8 so that the length of the stroke of the feeder 3 can be adjusted to suit the conditions. Above the feeder 3 and within the hopper are supported a number of loosely hanging bars 9 95 resting lightly on the steps 4 of the feeder.

The operation of the parts just described is: When the nails are poured into the hopper and the machine is operated, the feeder 3 moves backward with the down stroke of 100 the nailer and the nails in the hopper are pushed down one step thereon by the loosely hanging bars 9 so that on the return stroke of the nailer when the feeder travels forward the nails are carried forward in the 105 110

hopper and a few are fed over the edge of the hopper.

Immediately below the edge of the hopper, from which the nails fall, is placed the 5 double hopper 10 of the sliding conveyer. This hopper 10 is so constructed that as many nails will fall into one side thereof as will fall into the other. As each nail falls on the inclined side 11 of this hopper 10 its 10 head slightly retards its motion so that its point tends to fall into the conveyer 12 first, but in any case the nail when it reaches the conveyer 12 is held only by its head so that the shank of the nail hangs between the 15 sides of the conveyer. This conveyer, as is readily seen in Fig. 5, is double, so that the nails from each side of the double hopper 10 are thereby conveyed; and since all the mechanism relative to the convey- 20 ing and guiding of the nails, hereinafter described, is double, one part being on each side of the central axis of the machine, it will only be necessary to describe one each of said parts, since the other parts are the 25 duplicates thereof. The conveyer 12 has a portion 13 of its outer side cut away from under the hopper and bent outward and a chute 14 fastened to said outer bent part 13 so that if a nail has a defective head, or has 30 no head at all, it will fall into the conveyer directly from the hopper and through the opening thus formed in the side and out from the sides of the machine by way of the chute 14, thus ridding the machine of such 35 imperfect nails. The conveyer is supported at its forward and lower end from the framework of the nailing mechanism in an inclined position and rests at its upper rearward end on the agitator 15. This agitator 40 15 consists of a segment of a circle suitably mounted in the frame work, under the end of the hopper, and having its periphery 16 serrated and having a lever 17 secured to its axis and extending to and engaging the ver- 45 tical operating bar 18 of the whole machine, so that with every motion of the operating bar 18 the agitator will turn on its axis and will shake the inclined sliding conveyers 12 so that any nails hanging thereon will tend 50 to slide downward from the hopper 10 to the nailing mechanism. The lever 17 which connects the agitator 15 to the main oper- 55 ating bar 18 is slotted so as not to interfere with the motion of the bar 18.

Referring now to Figs. 3 and 7 to 14, as each nail arrives near the end of the sliding conveyer 12 it is intercepted by a pin 19 which passes horizontally through a hole in the sides of the conveyer 12 so that when 60 the nail which has been immediately before it and is on the other side of the pin falls from the end of the conveyer, the pin will not allow this nail to fall at the same time. This pin 19 is secured to the nail valve and 65 moves therewith. This nail valve consists of

a plate 20 extending across the machine in front of both of the conveyers 12, and having two vertical grooves 21 therein, so positioned that when the plate 20 is at one end of its stroke the grooves 21 are out of line 70 with the conveyers, and the pins 19 which are fastened to the plate, are withdrawn from the conveyers 12 so that the forward nail passes to the end of the conveyer 12 and rests on the plate 20 but can not move 75 further, and so that when the plate has moved to the other end of its stroke the grooves 21 are in line with the conveyers 12 and the end nails drop from the conveyers 12 into the grooves 21, and at the same time 80 the above mentioned pins 19 are projecting through the holes in the sides of the conveyers 12, preventing any more of the nails from falling thereinto. This plate 20 passes directly through the frame of the nail mech- 85 anism and is provided with a wedge-shaped projection 22 at a point near its center and within the frame work of the nailing mech- anism. The flat spring 23 is secured to the vertically moving nail guide hereinafter de- 90 scribed, and is so shaped as to engage and move sidewise this wedge-shaped projection 22 against the action of another spring 24 which also acts on the plate 20, so that when the nailing guide is at the top of its stroke 95 the plate 20 is in the position for allowing the end nail in the conveyers 12 to drop therefrom into the groove 21 therein, and as the nail guide moves downward it moves the plate 20 sidewise through the action of the spring 100 23 on the wedge 22, as above described. This action is accomplished by means of the spring so that if from any cause the plate should become blocked by a nail clogged therein, the downward stroke of the nailing 105 device will not break the mechanism, be- cause the spring will give sufficiently to re- lieve the strain. Under each of the ends of the conveyers 12 and in line with the grooves 21 of the plate 20 are fastened the chutes or 110 tubes 25 which lead the nails released by the plate 20 to the nailing mechanism.

The nailing mechanism consists of two vertically moving bodies, namely, the driver 26, which is secured to the main operating 115 bar 18 by means of a walking beam 27 or other suitable lever, and a nail guide 28 which is loose within the frame work of the nailing mechanism, but which is moved up- 120 wards by means of a lug or pin 29 formed on the driver 26, and which moves down- 125 ward, when relieved of the upward pressure of the driver 26, under the actions of spring 30. This nail guide 28 is formed substan- tially as is shown in Figs. 10 and 11 and has 130 at its lower end a pair of vertical holes 34 into which the nails fall, and through which the plungers 31 of the nail driver pass. The upper part of the nail guide 28 is offset out of line with the lower part, as is readily seen 130

in the drawings, and carries the above mentioned flat spring 23 by means of which the nail valve plate 29 is operated. A pin or lug 29 is secured to the nail driver 26 and engages 5 under the upper shoulder of the nail guide 28 so that when the driver 26 is raised to the top of its stroke it raises the nail guide 28 to the top of its stroke, but the nail guide 28 does not travel downward the full distance 10 that the driver 29 does but simply so far that its bottom end rests on the iron strip 32 being nailed, and as this position will depend on the thickness of the wooden strip 33 and of the iron strip 32, it naturally varies some- 15 what. The holes 34 through which the nails pass have side entrances 35 at their upper end which connect with the nail chutes or tubes 25 after the nail guide 28 is started downward on its downward stroke, as shown 20 in Fig. 13, but which are slightly above the nail chute or tube 25 when the nail guide 28 is at the top of its stroke, as shown in Fig. 12, thus preventing the nail, which starts to fall while the guide 28 is still rising, from 25 falling into the nail guide, but as soon as the nail guide 28 moves downward slightly the nail falls into the side hole 35 thereof and is directed down to the strip to be nailed and is held vertically in position by means of 30 this nail guide.

The nail driver consists of a main bar 26 having at its lower end two plungers 31 adapted to pass through the holes 34 in the nail guide 28 and to engage the heads of the 35 nails therein. The machine is mounted on a suitable table 36, the nailing mechanism being near the front edge thereof, and the main operating rod 18 passes downward from the walking beam 27, through an open- 40 ing in the table 36 and to a pedal 37, being however counterbalanced by a weight 38 adjustably secured on a lever 39 in such manner as to raise the rod 18 when the foot pressure is withdrawn from the pedal 37.

45 On one side of the machine is placed a gage 40 adapted to receive the free end of the iron strip 32. This gage 40 is adjustably secured to the top of a bar 41 whose end acts as a gage or stop for the nailing end of 50 the wooden strip 33. Since in practice the iron strips are cut the same length, it is evident that if the wooden strip is placed against the stop 41 in nailing position, and if the iron strip is placed with its end in the 55 gage 40, that the other end of the iron strip will lie in its proper nailing position. It is also evident that, since the exact position of

the nails are known, the nails may be driven much nearer to the ends of the strips 32 and 33 thus effecting a saving in the iron used, 60 since about one inch can be saved on each strip.

Having described my invention, what I claim is:

1. In a nailing machine, the combination 65 of a hopper having inclined sides and open end; a reciprocating feeder in said hopper and having steps formed thereon; means for reciprocating the feeder; and loosely hanging bars engaging the feeder and adapted to 70 prevent nails thereon from traveling backward with the backward motion of the feeder.

2. In a nailing machine, the combination 75 of a hopper having inclined side and open end; a reciprocating feeder in said hopper and having steps formed thereon and adapted to feed nails from the open end of the hopper; loosely hanging bars engaging the feeder and adapted to prevent nails thereon 80 from traveling backward with the backward motion of the feeder; a double hopper under the open end of the first hopper and adapted to divide the stream of nails; two inclined conveyers adapted to receive the nails from 85 the double hopper; an agitator adapted to shake the conveyers; means connecting the agitator to the feeder whereby the feeder is reciprocated with every movement of the agitator; and means for moving the agitator. 90

3. In a nailing machine, the combination 95 of a nail tube to which nails are delivered at intervals governed by the operating mechanism; a vertically moving nail guide adapted to close the nail tube when at the upper part of its stroke, but having a hole therein communicating with the tube when below the upper part of its stroke, said hole leading to the point where the nail is to be driven; a nail driver; means for reciprocating the nail driver vertically; a plunger formed on the nail driver and adapted to enter the hole in the nail guide to drive the nail; and a lug on the nail driver and adapted to engage the nail guide to raise the guide 100 when the driver is at the upper part of its stroke.

In testimony whereof I affix my signature in presence of two witnesses.

JOHN E. ELWING.

Witnesses:

CHARLES McCULLY,
LEONARD McCLEARY.
